APERTURE CLEANING MEANS FOR FLUID
DISTRIBUTING APPARATUS

Raymond P. Frye, Chicago, Ill.

Application September 15, 1939, Serial No. 295,085

6 Claims. (Cl. 299—59)

The invention relates to aperture cleaning means for fluid distributing apparatus and more particularly has reference to means for cleaning the drop discharging apertures of fluid distributing apparatus of the type disclosed in the copending application of Lucien I. Yeomans, Serial No. 295,030, filed September 15, 1939.

In the apparatus disclosed in the Yeomans application, fluid is distributed uniformly and in accurately measured quantity by means which includes a plurality of apertures, the size of which is one of the factors in the determination and control of the quantity of distributed fluid. More particularly, the aggregate quantity of fluid discharged from the machine is measured as a multiple of the quantity of fluid contained in each one of a number of drops. It is important for the sake of accuracy and uniformity that all of the drops contain a like quantity of fluid and the size of the discharge apertures is one of the factors that determines the quantity of fluid in the drops. Among the several uses to which the Yeomans apparatus may be put is the distribution of paint or other marking material to lumps of coal. Such fluid, and other fluids of similar character, tend sooner or later to clog the apertures, thus reducing their effective size and making it impossible accurately to calculate the quantity of fluid discharged from the apparatus.

An object of the invention is to provide a simple effective means for cleaning the apertures and dislodging any particles of material which may have accumulated therein.

Another object of the invention is to provide a new and improved aperture cleaning means of this character which is operatively associated with the distributing apparatus and normally occupies an out-of-the-way position thereon and is movable at the control of the operator from its out-of-the-way position to perform its aperture cleaning operation and then return to its normal position.

Other objects and advantages will become apparent in the following description and from the accompanying drawings, in which:

Figure 1 is a somewhat fragmentary view partially in longitudinal section of a distributing apparatus and an associated aperture cleaning means embodying the features of the invention.

Fig. 2 is a transverse section through the apparatus and is taken substantially along the line 2—2 of Fig. 1.

Figs. 3 and 4 are transverse sectional views through the apparatus taken along the line 3—3

of Fig. 1, and illustrate respectively two different operative positions of the cleaning means.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Since an exemplary form of apparatus embodying the present invention has been shown in association with the fluid distributing apparatus fully illustrated and described in the Yeomans application aforesaid, it is believed that only a brief description of such apparatus is here necessary. Thus, with reference to Fig. 1, the apparatus includes a dispensing tube 10 of substantial diameter and desired length secured at each end to a bracket 11. The brackets are arranged operatively to associate the apparatus with some part or mechanism containing or presenting the material to be treated. For example, the part may be the frame of an endless conveyer.

The lower portion of the tube has one or more series of longitudinally aligned discharge apertures 12 therein. Within the tube is a cylindrical member or roll 13 supported on a shaft 14 for rotation therewith. The roll is preferably formed of rubber or like material, is of smaller external diameter than the internal diameter of the tube, and is so related to the tube that the roll has a wiping engagement with the tube along the longitudinal line of the apertures 12. Peripheral contact between the roll and tube along this line will close the apertures and prevent the escape of fluid therethrough. The roll, however, is provided with a circumferentially uniformly spaced series of longitudinally extending grooves 15 which open at each end of the roll into fluid chambers 16 within the tube and brackets 11. The fluid to be distributed is delivered to the tube under suitable pressure (which may be variably adjusted) through a distributing system which includes an inlet conduit 17 leading to a chamber 16 at one end of the roll, a return conduit 18 leading back to the system from the chamber 16 at the opposite end of the roll, and a drainage conduit 19.

When the roll is driven through suitable means indicated generally at 20, the grooves 15 successively open the apertures 12, and a drop of material will be discharged from each aperture.

The quantity of fluid in each drop so discharged depends on several factors, among which are the speed of roll rotation, the pressure on the fluid to be distributed, and the area of each aperture 12. According to the present invention, means is provided for removing accumulations of material in or about the apertures 12 to maintain constant the area which is a basic factor in the calculations determining machine operation.

At each end of the tube beyond the end apertures therein is a collar 21 preferably comprised of two semi-circular sections secured together as by bolts 22. An upwardly extending ear 23 is formed on each top section and the ears provide bearings for the ends of a transversely extending rock shaft 24. An actuating arm 25 (Figs. 1 and 2) is pinned, as at 26, to the rock shaft and the swinging end of the arm is pivoted between the bifurcated ends of a reciprocable rod 27 by which the shaft is rocked. Such means as a hydraulic or pressure fluid actuated piston, operable in the cylinder 28, may be employed to drive the reciprocating rod. The system for supplying pressure fluid to the cylinder is not shown since any conventional system, conveniently controllable by the operator, may be used.

The aperture cleaning means is supported from the rock shaft 24 normally in a retracted out-of-the-way position with respect to the apertures and is connected with the rock shaft in the present instance by means which, upon movement of the rock shaft in one direction, advances the cleaning means from its retracted position into alignment with the apertures and then moves the cleaning means into and through the apertures. As may best be seen in Figs. 1 and 3, the cleaning means includes a generally U-shaped frame comprised of a base bar 29 and end supports 30 arranged in assembly to be disposed immediately adjacent to the inner sides of the ears 23.

The base bar is an angularly shaped member having a substantially vertical leg through which the member is secured to the end supports with the other leg disposed adjacent to the tube and projecting generally horizontally away from the end supports. The horizontal leg carries a series of pins 31 having the same alignment and spacing as the apertures 12, and dimensioned to fit the apertures snugly yet slidably. Each end support, as shown in Fig. 3, beyond the base bar has an arcuate section designated 32 arranged to extend substantially half-way around the tube 10 and terminating at its other end in an outward extension 33. Each extension has a boss 34 defining a bore 35 for the rock shaft 24. The bores 35 are elongated in a direction which parallels the axes of the apertures 12. Above the bosses 34, each extension 33 has a second boss 36 provided with an elongated slot 37 extending substantially at right angles to the line of elongation of the associated bore 35. The actuating connections between the rock shaft and the end supports 30 as shown in Figs. 1 and 3, include arms 38 pinned as at 39 to the rock shaft and having outwardly extending pins 40 at their swinging ends engageable within the slots 37. A return spring 41 is connected to a pin 42 on an extension 33 and to a stationary part, such as the member 43 on the bracket 21.

The operation of the device will best be understood by consecutive consideration of Figs. 2, 3 and 4, which illustrate respectively the po-

sition of the parts when retracted, when advanced to move the cleaning pins into alignment with the apertures 12, and when the cleaning pins are moved into the apertures. In the relationship of the parts shown in Fig. 2, the frame of the cleaning means hangs from the rock shaft 24 and is swung to a retracted position by the engagement of the pins 40 with the ends of the elongated apertures 37 that advance when 5 the cleaning means swings to its retracted position. It will be noted that in this position of the parts, the arms 38 are located beyond the line of elongation of the bores 35 so that initial movement of the rock shaft in a counterclockwise direction, as viewed in Fig. 3, produces a swinging movement of the frame toward the tube 10 about the rock shaft as an axis to dislodge the cleaning pins in axial alignment with the bore. This position is determined by the engagement of the vertical leg of the base bar 29 with stop lugs 44 on projections 45 formed on and depending from the lower sections of the collars 21. During the swinging movement of the frame, the pins 40 move only slightly along 10 the lengths of the elongated apertures 37 and the frame is suspended from the rock shaft 24.

Upon engagement of the frame with the stop lugs 44, continued movement of the rock shaft causes the pins 40 to travel along the apertures 30-37 and exert a camming action which shifts the frame upwardly against the tension of the spring 41. The upward shifting movement is guided at the top of the frame by the engagement between the rock shaft and the elongated bores 35, 35 and at the bottom of the frame by the abutment between the base bar and the stop lugs 44. As the frame shifts, the cleaning pins are moved toward and into the apertures thereby breaking away and removing all material which may have 40 accumulated in or immediately adjacent to the apertures. When the rock shaft is moved in the opposite direction, the spring 41 and the camming action of the pin 40 in the slot 37 first moves the pins in a straight line direction to 45 clear the apertures and thereafter swings the frame to its retracted position.

It will be evident from the foregoing that a simple and effective means has been provided for cleaning the apertures of fluid distributing apparatus. The device is comparatively inexpensive to construct and is simple and efficient in its operation. Moreover, it is instantly available for use and may be actuated without interfering with the operation of the distributor.

I claim as my invention:

1. In a device for cleaning the discharge means of distributing apparatus, the combination of cleaning means, a support for said cleaning means movable to dispose said cleaning means in a position of alignment with said discharge means and then into operative engagement with said discharge means, means for determining said position of alignment and for guiding the engaging movement of said cleaning means, and means for moving said supporting means.

2. In a cleaning device for the discharge means of fluid distributing apparatus, the combination of a frame having cleaning means thereon arranged for operative association with said discharge means, a rock shaft, means for swingably supporting said frame from said rock shaft and for shifting movement transversely of the axis thereof, connecting means between said rock shaft and said frame including cam means for first swinging said frame to align said cleaning

means with said discharge means and then shifting said frame to effect engagement of said cleaning means with said discharge means, spring means acting on said frame in a return direction, and means for actuating said rock shaft.

3. In a device for cleaning a plurality of discharge apertures in a fluid distributing apparatus, the combination of a frame having a plurality of cleaning pins thereon arranged to enter and clean said discharge apertures, a rock shaft, means loosely supporting said frame, connecting means between said rock shaft and said frame including means for swinging said frame to aline said pins and apertures, and means for shifting said frame to move said pins into said apertures, and means for actuating said rock shaft.

4. In a cleaning device for the discharge means of fluid distributing apparatus, the combination of a frame having cleaning means thereon arranged for operative association with said discharge means, a rock shaft, said frame having alined bearing apertures therein for said rock shaft, said apertures being enlarged to permit said frame to shift relative to said rock shaft, connecting means between said rock shaft and

said frame for swinging said frame to aline said cleaning means with said discharge means, and cam means effective when the parts are thus alined to shift said frame to effect engagement of said cleaning means with said discharge means, and means for actuating said rock shaft.

5. In a device for cleaning the discharge means of distributing apparatus, the combination of cleaning means for said discharge means, supporting means for said cleaning means, means for moving said supporting means to dispose said cleaning means in alinement with said discharge means, and means for moving said supporting means to carry said cleaning means into operative engagement with said discharge means.

10 6. In a device for cleaning the discharge means of distributing apparatus, the combination of means for cleaning said discharge means, a movable support for the cleaning means including means for guiding the movements thereof first 20 to swing said cleaning means into alinement with said discharge means and then with a straight line movement into cleaning engagement with said discharge means, and means controlled by the operator for moving said cleaning means.
